DESIGN FOR A SADIRON CASING

Russell I. Huffman, Strasburg, Ohio, assignor to Dover Manufacturing Company, Dover, Ohio, a corporation of Ohio

Application September 10, 1935, Serial No. 58,504

Term of patent 7 years

To all whom it may concern:—

Be it known that I, Russell I. Huffman, a citizen of the United States and a resident of Strasburg, in the county of Tuscarawas and State of Ohio, have invented a certain new, original, and ornamental Design for a Sadiron Casing, of which the following is a specification, reference being had to the accompanying drawing, forming part thereof.

I claim:

The ornamental design for a sadiron casing substantially as shown.
